CLAIM

The ornamental design for a splicer for magnetic tape, substantially as shown and described.

DESCRIPTION

FIG. 1 is a perspective view of a splicer for magnetic tape, showing our new design;

FIG. 2 is a side elevational view thereof;

FIG. 3 is a right end elevational view thereof;

FIG. 4 is a left end elevational view thereof;

FIG. 5 is a top plan view thereof.

The bottom of the device is substantially planar and unornamented.
